UNITED STATES PATENT OFFICE.

MARIE J. LANG, OF PEORIA, ILLINOIS.

CORSET.

No. 803,204.

Specification of Letters Patent.

Patented Nov. 10, 1908.

Application filed January 30, 1908. Serial No. 413,488.

To all whom it may concern:

Be it known that I, MARIE J. LANG, citizen of the United States, residing at Peoria, in the county of Peoria and State of Illinois, have invented certain new and useful Improvements in Corsets; and I do hereby declare that the following is a full, clear, and exact description of the invention, which will enable others skilled in the art to which it 10 appertains to make and use the same.

This invention relates to improvements in corsets, pertaining more particularly to a corset for general use as well as one adapted for use by women of delicate organism and 15 those approaching maternity.

One of the objects of the invention is to provide a corset which will properly support the busts and the abdomen; that portion of the corset which usually intervenes 20 between these two positions being eliminated to leave the lungs, heart, stomach and liver free and uncramped.

A further object is to provide a corset that will readily yield to all movements of the 25 wearer without placing any undue pressure and without restraint upon any part of the body.

In the appended drawing, Figure 1 is a rear view of the corset. Fig. 2 is a side view. 30 Fig. 3 is a front view. Fig. 4 is a side view of a portion of the corset shown in the first three figures showing an attachment; and Fig. 5 is a perspective view of the attachment shown in Fig. 4.

The corset comprises a back portion indicated at A provided with a number of whale-bone or other suitable supports or stays B which will readily adapt themselves to the form of the wearer and to all movements by reason of their yielding qualities. To the edges of said back is suitably secured 35 a series of horizontally disposed elastic webbings C at each side. These said webbings preferably occupying a position at the sides 40 of the wearer, their forward ends having attached thereto a flexible strip or stay E which forms the termination of the middle portion of the corset as shown. To each stay, at opposite sides of the corset, is secured a flap F each of which extends around 45 in front of the wearer and attached to one another at the front by means of hooks or other suitable device indicated by G, these 50 said flaps being utilized in the same manner as the ordinary corset for supporting the bust and having flexible stays at F', there be-

ing suitable supporting straps H extended over the shoulders and attached to the back A and adjustably secured to the said flaps F by any good means, as, for instance, by 55 buckles J, the said supporting straps serving to hold the flaps F in the proper position. Attached also to the stays E near the bottom are flaps K at each side, as shown in Fig. 3, to each pair of which is attached a flap L provided with stays L' by means of 60 buckles or other suitable devices M by which 65 said flaps may be adjusted. The latter are provided with hooks or other suitable devices indicated at N for fastening their adjacent edges together at the front. Suspended from each flap at the front is a tab O to which the hose supporters P are attached in the usual manner. These supporters serve to hold the flaps in the proper 70 position to support the abdomen so that the wearer will have the proper form and appearance, it being understood that by adjusting the flaps K the abdomen may be held 75 back, especially when used by a person of 80 heavy build. The corset thus constructed and arranged is well adapted to persons of all builds, whether slim or portly. In addition to the adjustments described herein, I 85 have provided a lacing A' in the back of the device by which, if desired, the wearer may 90 adjust it to any desired size, or for imparting to the figure any desired form of outline. Where persons are of large or portly build or those afflicted with complaints peculiar to 95 their sex the corset affords them perfect 100 comfort since it yields to all movements and fits the figure perfectly and from the further fact that the lungs, heart, stomach and liver are left entirely free instead of being cramped 105 as results with the corsets usually constructed.

I have provided an attachment for my improved device which I am now about to describe and it will be noted that in the first four figures I have shown attached to the corset a hook at each side, as at Q and one at the back indicated by R. The attachment referred to is shown in full in Fig. 5 while in Fig. 4 it is shown in connection with the 110 corset. Said attachment consists of a back portion S having various flexible stays as at T to hold it in shape and to adapt itself to the form of the wearer. Upon its top edge are secured eyelets U' which engage the hooks Q and R just described. The extremities of said portion S terminate preferably

at the sides of the wearer each being provided with elastic webbings U similar to and for the same purpose as those of the corset at C. It is further provided with 5 flaps V to which are secured buckles W or other adjusting devices which receive the tabs 1 of flaps 2 constructed after the manner of the flexible flaps L of the corset said flaps L having suitable hooks 3 for fastening 10 purposes and provided also with flexible stays 6 such as have been hereinbefore described. These flaps act as a firm support for the abdomen and answer admirably when properly adjusted for times of maternity.

15 Upon the flaps B are depending tabs 4 and on the flaps 2 at the front thereof are similar tabs 5 to all of which the supports are attached, the latter serving to properly hold the supporting flaps in position. By 20 means of the said buckles W, or such other devices of like nature that may be used, these supporting flaps can be adjusted to suit circumstances.

I consider, as a good deal of importance, 25 the open front portion of the corset between the positions of the bust and the abdomen which, in so far as my knowledge goes, I believe to be entirely new. The advantages of such a construction are readily apparent after 30 what has been herein stated with regard thereto. The device is of two fold value for the reason that it is readily convertible, by the means described, from an ordinary corset, by which the wearer may preserve a 35 desired form of outline of figure, to one adapted for use by persons who are in a delicate condition. My improved corset is admirably adapted for persons doing their daily household work or for those who may 40 indulge in strenuous exercises where full movement of the body and its parts are required and where there should be no cramping of the organs.

As distinguished from other corsets of 45 which I am aware, mine by being provided with the flexible side strips E beneath the arms and those at the back adjacent thereto and referred to as B and connecting the former with the said adjacent ones by the 50 horizontally disposed elastic webbings C, I am enabled to preserve a graceful form of outline at the sides as readily as do usual forms of corset. The stays B referred to likewise preserve the proper outline in the 55 small of the back so that as a matter of fact the ordinary observer can see no difference in the outline of the wearer, while the corset affords comfort not found in the ordinary kind.

60 By extending horizontally it is evident that each portion C above mentioned, readily conforms to and supports those portions of the wearer necessary to preserve the lines mentioned, aided partially by the vertically 65 disposed stays to which they are attached.

When about to use the attachment shown in Figs. 4 and 5 the flap portions L may be either removed from the corset or allowed to remain in place, it being entirely optional with the wearer which plan is employed. 70 In removing these portions the buckles K will be removed therewith so that there will be no discomforting parts to be forced against the flesh by said attachment when in place. Fig. 4 shows one of the tabs or 75 flaps K from which the portion is removed.

I desire to state that I may alter the construction or arrangement slightly and provide equivalent means for any of the parts described without departing from the spirit 80 or intent of the invention.

Having thus described my invention, I claim:

1. A corset comprising a body or back portion, flexible vertically disposed side 85 members, horizontally disposed elastic media connecting the said side members with the body or back portion, a bust supporting portion attached to the upper portion of said side members, and an abdominal supporting- 90 portion supported from the lower portion of said side members the said bust portion and abdominal portion being separate members and separated from one another, there being an open space between them substantially as 95 described.

2. A corset comprising a body or back portion, flexible vertically disposed side members, horizontally disposed media connecting the side and back portions, a bust 100 supporting portion connected to the side members, and an abdominal support also attached to the side members and separate from the said bust portion.

3. A corset comprising a body or back 105 portion, flexible vertically disposed side members, horizontally disposed media connecting the side and back portions, a bust supporting portion connected to the side members, supporting means for said bust 110 portion, an abdominal support also connected to the side members, and separated from the bust portion, there being an open space between the bust support and the abdominal support such open space extending 115 to the side members.

4. A corset comprising a body or back portion having vertical flexible stays, flexible vertically disposed side members arranged to have a position beneath the arms 120 of the wearer, horizontally disposed elastic media connecting the side members and the back portion, a bust supporting portion attached at the sides, and an abdominal support also attached to the sides and separate 125 from the bust portion.

5. A corset comprising a body or back portion having vertical stays, flexible vertically disposed side members arranged to have a position beneath the arms of the 130

wearer, horizontally disposed elastic media connecting the side members and the back portion, a bust supporting portion attached at the sides, and a detachable abdominal support attached at the sides.

6. A corset comprising a body or back portion, bust portions having flexible stays, horizontally disposed elastic media interposed between and connecting the back and 10 said bust portions, and extending the full height of the corset at the sides of the wearer, flexible non-elastic abdominal portions below the bust portions and members attached to said elastic media below the place 15 of connection of the bust portions and having the said abdominal portions adjustably and removably attached thereto.

7. In a corset, a back or body portion, 20 flexible side members extending substantially the full height of said back elastic media connecting said side members with the back portion, a front bust portion attached to the side members, a detachable abdominal supporting portion and adjustable devices 25 connecting the latter with said side members.

8. In a corset, a back or body portion, adjusting means therefor, flexible vertically disposed side members, elastic media con-

necting the latter with the said body portion, a bust supporting portion attached to the 30 side members, supports therefor, an abdominal support also connected to the side members, but entirely separate from the bust portion, said abdominal support being detachable, and means for attaching the stock- 35 ing supporters thereto.

9. In a corset a back or body portion, means on said portion for adjusting it, flexible vertically disposed side members, elastic media connecting the latter with the body 40 portion, a bust supporting portion attached to the said flexible side members at the upper part thereof, supporting members extending over the shoulder and attached to the said bust supporting portion and said back, a 45 detachable abdominal support, device secured to the side portions, near the lower end thereof and having the abdominal support adjustably connected thereto substantially as set forth and described. 50

In testimony whereof I affix my signature, in presence of two witnesses.
